UNITED STATES PATENT OFFICE.

GEORGE BOEMERMANN, OF NEW YORK, N. Y.

MEANS FOR PROPELLING VESSELS.

SPECIFICATION forming part of Letters Patent No. 653,435, dated July 10, 1900.

Application filed November 23, 1899. Serial No. 738,051. (No model.)

To all whom it may concern:

Be it known that I, GEORGE BOEMERMANN, a citizen of the United States, residing in the city of New York, borough of Brooklyn, county 5 of Kings, and State of New York, have invented certain new and useful Improvements in Means for Propelling Vessels, of which the following is a specification.

This invention relates in general to means 10 for driving a boat or vessel having as a propelling device a screw-propeller; and the object is in part to provide for the submersion of the antifriction bearings and gearing of the propeller-shaft in water, whereby the friction 15 is reduced to a minimum, in part to means whereby the propeller may be driven by hand by two or more persons through the medium of hand-cranks, and in part to means whereby the passage or conduit which leads the 20 water of flotation to the gearing and bearing boxes may be cut off at will.

In the accompanying drawings, which illustrate an embodiment of the invention, Figure 1 is a side elevation, on a small scale, of a boat provided with the improved propelling mechanism, the side of the boat being partly broken away in order to disclose the mechanism inside thereof. Fig. 2 is a sectional view of one of the boxes inclosing the gearing with 25 the propeller-shaft, and Fig. 3 is a similar view of the gearing and bearings of the upright shaft. Figs. 4 and 5 are sectional detail views of the means for shutting the water from the tube or casing inclosing the propeller-shaft. Figs. 6, 7, and 8 are detail views 30 of the thrust-bearings of the propeller-shaft.

Referring primarily to Figs. 1 to 3, inclusive, *a* represents a boat; *b*, the rudder thereof; *c*, the propeller for driving or propelling 40 the boat, and *d* the propeller-shaft. These parts in themselves have no special novelty.

The boat may have one or more sets of crank mechanisms for driving the propeller-shaft, the number being dependent somewhat 45 on the size of the boat. In Fig. 1 two of such devices are shown, one of which is illustrated in detail in Figs. 2 and 3.

Fixed in the bottom of the boat are two gearing-boxes *e*. The after box is by preference connected with the stern-post of the boat by a tube *f*, and the two boxes are connected together by a similar tube *g*. These

tubes are alined, and the propeller-shaft extends through them and through the after box, being thus entirely housed inside of the 55 boat. Fig. 2 shows the box seen at the left in Fig. 1, and Fig. 3 the box at the top of the pillar which supports the cranks; but as both of the crank mechanisms for driving are or may be alike a description of one will suffice. 60

On the box *e* is fixed a pillar *h*, on which is rotatively mounted a crank-shaft *i*, having on its respective ends suitable cranks *j*. On the shaft *i* is secured a bevel gear-wheel *k*, which gears with a bevel pinion or wheel *m* 65 on an upright shaft *n* in the pillar *h*. On the lower end of this upright shaft is fixed, Fig. 2, a bevel-wheel *o*, which gears with a bevel pinion or wheel *p* on the propeller-shaft. The upright shaft *n* has roller-bearings above and 70 below. The bearing-box *q* below, Fig. 2, has a support in the box *e*, which support straddles the propeller-shaft and is in the nature of two legs *r*, one of which is seen in Fig. 2. This box is in the form of an upright cylinder 75 with a removable cap *s*, and incloses a series of bearing-rollers *t*. The rollers are arranged in pairs, two on each shaft *u* and distanced by a ring *v* between the rollers of the pairs and through which the shafts extend. The 80 bevel-wheel *o* has a hollow hub or boss which incloses the box *q* and permits the wheel *o* to fit down closely to the propeller-shaft. At the upper end of the pillar *h* the shaft *n* has a similar roller-bearing within the cap *h'* of 85 the pillar, as indicated by dotted lines in Fig. 3. In this case the cap *h'* forms the bearing-box for the rollers. The cap *h'* is mounted on a box *h''*, Fig. 3, within which is an end or thrust bearing *w* for the shaft *n*. As this 90 bearing is not an essential for the upright shaft and is in substance the same as that used on the propeller-shaft, a description of the latter, with especial reference to Figs. 2, 6, and 7, will suffice.

In the box *e* at the end of the propeller-shaft is fixed a bearing-block *x* about the latter, and fixed on the shaft at opposite sides of said bearing-block are two disks *y*. Between the respective disks and the bearing *x* are collars *z*, loose on the shaft, and bearing-rings *1*. Each collar *z* and ring *1* serve as supports for the journals on which turn conical rollers 2, that roll on circular tracks 3 on the faces of

the bearing-block x and the disks y when the shaft d rotates. The ring 1 prevents the rollers from being forced radially outward by the pressure. Preferably, these rollers will be flanged at their ends, as shown, and to insure their rotation they may have on one or both ends cogs or teeth to gear with racks along the tracks over which they roll. This geared construction is shown in the fragmentary view, Fig. 8, wherein 4 represents the gears on the ends of the roller 3, and 5 the racks. One of the disks y serves to take the thrust when the boat is moving ahead and the other takes the thrust when it is backing.

15 It will be noted that the propeller-shaft does not have a bearing or need not have a bearing, properly so called, in the block x . This block is designed to resist the end thrust of the shaft d , which will have a roller-bearing 20 (seen clearly in section in Fig. 2) between the pinion p and the thrust-bearing. If there be two crank mechanisms, as seen in Fig. 2, the shaft d will extend entirely through this box and there will be or need be no thrust-bearing 25 therein.

The gearing k m will be housed in a casing h^3 , mounted on the pillar h , and the crank-shaft i has or may have antifriction-roller bearings (see Fig. 3) similar to or like those 30 for the shafts d and n .

The tubular casings f and g and the boxes e are filled with water, and this submergence of the bearings and gearing in water deadens the rattle and noise of the gearing and lubricates the latter; but in order to prevent the water from entering the boat in case of accident to the casings or boxes or in case it is desired to open the boxes or casings for repairs means are provided for cutting off the 35 access of water to the casing f . This cut-off is seen at 26 in Fig. 1 and is illustrated in detail in Figs. 4 and 5. The casing f has in it an enlargement or box 27 with a removable front plate 28, and in this box is a clamp ring 40 or device 30, adapted to be operated by a collared screw 31, provided with a suitable crank or operating handle. The clamp or ring 30 is held in place by a hinge-pin 32, (seen in Fig. 5,) and it has a cut packing-ring 33, which 45 embraces the propeller-shaft. Normally the ring 33 springs open, so as not to touch the shaft d ; but if it be desired to cut off the influx of water it may be clamped thereon by means of the screw 31, when it will act, in 50 conjunction with the ring 30, as a valve to check the flow of the water through the casing f . Obviously this closure of the valve will be effected when the propeller-shaft is not in operation.

55 It will be obvious that some variation may be made in the construction shown without materially departing from the present invention. For example, the clamp device 30 might be in two sections of any form, as the main 60 function of this device is to close the ring 33 on the propeller-shaft. It will also be obvious without further illustration that if the

two disks y were loose on the shaft d and fixed in the box e and the part x were fixed on the shaft and loose in the box the operation would be the same, or, in other words, if there were two blocks x and one double-faced disk y between them and fixed on the shaft the operation would be the same as with the construction shown. Obviously, also, 75 there may be a disk y to resist the thrust in backing in one box e and a disk y to resist the thrust in going ahead in the other box. In this case there would be a bearing-block x in each box.

Having thus described my invention, I claim—

1. The combination with a boat, a propeller-shaft mounted therein, a propeller on said shaft, driving-gears at two points along said shaft, and upright shafts at these points gearing with the propeller-shaft, of two boxes e , inclosing the gearing at the said points, a tube g inclosing the propeller-shaft and connecting said boxes, a tube f inclosing the propeller-shaft and extending from the after box to the stern of the boat and open to the water of flotation, and an antifriction-bearing in one of said boxes to take the end thrust of the propeller-shaft, whereby the gearing and 95 said thrust-bearing are submerged.

2. The combination with a boat, a propeller-shaft mounted therein, and a propeller on said shaft, of a box inclosing said shaft at the point where the driving-gears are situated, the said gears, the driving-shaft, a casing f , connecting said box with the boat at the point where the propeller-shaft passes out, and a cut-off in said casing, whereby the influx of water may be stopped at will.

3. The combination with a boat, a propeller-shaft mounted therein, and a propeller on said shaft, of a box inclosing said shaft at the point where the driving-gears are situated, the said gears, the driving-shaft, a casing f , connecting said box with the boat at the point where the propeller-shaft passes out, and a cut-off in said casing near its outer end, said cut-off comprising a box 27, in the casing f , a cut packing-ring 33, embracing the 115 propeller-shaft, and means for clamping said ring on the shaft.

4. The combination with the boat, the propeller-shaft mounted therein, and the propeller on said shaft, of the roller, end-thrust bearing for the propeller-shaft, the roller shaft-bearing therefor, the pinion p on the propeller-shaft, the upright driving-shaft, the wheel o thereon gearing with the pinion p , said wheel having in it a hollow to receive an antifriction-roller bearing for the driving-shaft, the said roller-bearing, and a box e inclosing all of said bearings and gearing and connected with the water of flotation for submerging the same, substantially as set forth.

5. The combination with a boat, a propeller-shaft mounted therein, a propeller on said shaft, an upright shaft geared below to the propeller-shaft and above to a crank-shaft

for operation by hand, the said crank-shaft, provided with cranks, and antifriction thrust-bearings for the propeller-shaft, of a casing inclosing the propeller-shaft, the gearing to the upright shaft, and the thrust-bearings, said casing being open to the water of flotation, and means for cutting off the influx of water to the said casing.

In witness whereof I have hereunto signed my name, this 20th day of November, 1899, in the presence of two subscribing witnesses.

GEORGE BOEMERMANN.
